UNITED STATES PATENT OFFICE.

WILLIAM L. THIEDEMANN, OF MUSKEGON, MICHIGAN, ASSIGNOR TO THIEDEMANN-HARDY COMPANY, OF MUSKEGON, MICHIGAN, A COPARTNERSHIP COMPRISING WILLIAM L. THIEDEMANN AND HAZLETT M. HARDY.

DENTAL TOOL HOLDER.

Application filed December 15, 1921. Serial No. 522,486.

To all whom it may concern:

Be it known that I, WILLIAM L. THIEDEMANN, a citizen of the United States, residing at Muskegon, in the county of Muskegon and State of Michigan, have invented certain new and useful Improvements in Dental Tool Holders, of which the following is a specification.

This invention relates to dental apparatus but more particularly to handpieces for use with dental engines and has for its primary object to provide a device which is simple in construction, efficient in operation and easily cleaned.

These handpieces are used to hold and operate a rotary tool which is inserted in the mouth of the patient, and it is particularly important that the construction may be quickly and easily disassembled for the purpose of sterilization and cleaning. It is impracticable to attempt to sterilize the assembled handpiece as this tends to solidify or destroy the lubrication and produces rust without removing the grit. The assembled handpiece cannot be adequately lubricated without using an excess of oil which subsequently will be released in the patient's mouth. In order to eliminate these objectionable features a construction has been devised which will permit practically the entire handpiece to be almost instantly disassembled, or assembled, without the use of any tools. The individual parts may then be thoroughly sterilized, cleaned and given a thin coating of oil prior to assembling.

Further important features of the invention are to eliminate joints which may become loose during the operation of the device, to provide an improved holder to receive the bur or other operating tool, to facilitate the connection of the handpiece with the driving shaft, and in general to provide a new and improved handpiece for the purpose described.

The many other objects and advantages of the invention will be better understood by reference to the following specification when considered in connection with the accompanying drawing illustrating a selected embodiment thereof, in which:—

Fig. 1 is a central longitudinal section of a type of handpiece embodying my invention.

Fig. 2 is a top plan view of the outer end

portion of the handpiece showing the parts in the position to receive the operating tool.

Fig. 3 is the same as Fig. 2, showing the tool locked in operative position, and

Fig. 4 is an elevation of one type of operating tool.

Referring to the drawings, the handpiece 5 is adapted to be secured upon the end of the flexible driving cable by the usual spring connection (not shown) which is provided at its end with a threaded ferrule to receive the shank 6 on the inner end of the sleeve 7 of the handpiece. The inner end of the driving shaft 8 is threaded to receive a dog 9 which is provided with a spur 10 to form an interlocking connection with the outer 70 end of the main driving shaft.

A slip joint sleeve 11 is splined upon the sleeve 7 and is provided with the usual spring latch 12 which engages a notch 13 in the sheath 14 of the handpiece. A forwardly projecting pin 15 on the sleeve 11 is adapted to enter a slot 16 in the sheath 14 to prevent relative rotation of these parts when in their assembled position. The forward end of the shaft 8 is longitudinally slidable 80 within a sleeve 17 and is provided with a laterally projecting lug 18 which enters the slot 19 in this sleeve, in order that the rotation of the shaft shall cause a corresponding rotation of this sleeve. The end portion 85 of the shaft 8 is longitudinally slotted at 20 and a serrated cam face 21 is formed on a web connecting the walls of this slot. The cam face 21 is engaged by the inner end of the cam lever 22 which has its opposite end pivotally connected to the sleeve 17 at 23. This cam lever 22 is provided with an operating nose 24 which engages the head of a plunger 25 seated in a plunger block 26 longitudinally slidable within the sleeve 17. 95

The forward end of the plunger block 26 is provided with a conical recess 27 which fits the correspondingly shaped end of the double end chuck 28. The forward end 30 of the sleeve 17 is contracted to form a conical recess 31 similar to the recess 27 only reversed in position, so that when the plunger is forced outwardly by the lever 22 both ends of the chuck are tightly compressed upon the shaft 29 and this shaft is locked to the sleeve 17. The chuck 28 is divided longitudinally to permit this compression. The inner end of the shaft 29 is

preferably extended within the plunger block 26 in order to provide a long bearing for the shaft and thus insure accurate driving action.

5 A tool holder 32 fits over the forward end of the sheath 14 and is prevented from rotation relative thereto by the pin 33 which enters the slot 34 in the tool holder 32. A bit-locking device 35 is secured upon the 10 tool holder 32 by the stud screw 36. This bit-locking device consists of a thin plate of spring metal which is provided with a longitudinal slot 37 through which the screw 36 passes. The inner end portion 38 of the slot 15 37 is preferably enlarged to permit the plate to be removed from the tool holder without the removal of the screw. A pin 39 projects laterally from the outer end portion 20 of the sheath 14 to enter a perforation 40 in the inner portion of the plate 35 and forms a locking engagement between the tool holder 32 and the sheath when the pin is within the perforation, as shown in Fig. 3. The plate 35 is provided near its outer 25 end with arcuate slots 41 and 42. The slot 41 is adapted to receive the upper end of the operating tool 43 to retain this tool within the holder. The walls of the slot enter the groove 44 in the tool. The slot 42 is adapted to receive a small stud screw 45 on the outer end of the tool holder to firmly position the outer end portion of the plate 35. A small stud 46 is provided in the plate 35 to enter a slight depression 47 in the face of 30 the tool holder.

35 The outer end of the shaft 29 is provided with a star-wheel 48 which is adapted to mesh with a corresponding gear 49 formed on the spindle sleeve 50. The spindle sleeve 40 50 extends through the passage 51 in the outer end of the tool holder and is provided with positioning collars 52 and 53. The collar 52 forms a shoulder which acts against the corresponding shoulder 54 produced by 45 the contraction of the lower portion of the passage 51. The collar 53 fits within the normal bore of the passage to support the upper end of the sleeve. The sleeve 50 is retained within the passage 51 by the plate 50 35 when this plate is in its latched position, as indicated in Fig. 3. The operating tool 43 passes through this sleeve and is prevented from relative rotation therein by the formation of the upper portion of the tool 55 socket which engages the cutaway portion 55 of the tool in the usual manner.

60 To permit a tool to be inserted into the handpiece, the plate 35 forming the bit-locking device is brought into the position indicated in Fig. 2. The tool is then inserted into the mouth of the spindle socket in the usual manner and pressed inwardly until the shoulder formed by the cutaway portion 65 55 of the tool engages the contracted upper end of the socket, as indicated in Fig. 1.

The plate 35 is then swung upon the screw 36 as a pivot into the position indicated in Fig. 3, the inner end of the plate being lifted to permit it to pass over the pin 39, and then released when the pin is in registration with the perforation 40. The tool is removed from the holder by lifting the inner end portion of the plate 35 to release the pin 30 and then swinging it into the position indicated in Fig. 2.

70 The rotation of the tool is started by drawing the sleeve 7 outwardly from the sheath 14 which is permitted by the splined connection of this sleeve with the slip joint sleeve 11. This movement causes the inner end of the lever 22 to be forced outwardly by the cam face 21 and to thus force the nose 24 against the head of the plunger 25. The plunger acts against the double end clutch 38 to frictionally bind the shaft 29 to the sleeve 17 and thus causes this shaft to be rotated by the shaft 8. The rotation of the shaft 29 causes the sleeve 50 and the tool 44 to be correspondingly rotated. To stop the 80 operation of the tool, the sleeve 7 is merely pressed forwardly into the sheath. This movement of the sleeve carries the cam face 21 forwardly and releases the pressure of the lever 22 on the plunger 25. The spring clutch 28 now expands and releases the 90 shaft 29.

95 Assuming that the handpiece is assembled and connected in the manner illustrated in Fig. 1, the parts are disassembled in the following manner:

100 The tool is removed by releasing the plate 35 in the manner previously described. The latch 12 is then disconnected from the notch 13 in the sheath 14 and the sleeve 7 withdrawn. The withdrawal of the sleeve 7 carries with it the sleeve 17 and the parts contained therein. The disengagement of the plate 35 with the pin 39 permits the tool holder 32 to be withdrawn by a straight longitudinal movement. The withdrawal of the tool holder releases the shaft 29 and permits this shaft to be withdrawn from the forward end of the sheath. The sleeve 50 may next be withdrawn from the tool holder by merely inverting the angle piece from the position indicated in Fig. 1 and tapping it lightly if this sleeve does not drop out without assistance. Further disassembling 110 of the parts will not usually be necessary. The assembling operation is equally simple and merely the converse of disassembling.

115 When the parts have been disassembled in the manner described, they are easily sterilized and all grit and foreign matter removed therefrom. Before reassembling the handpiece, the parts should be given a light coating of oil, which thoroughly lubricates the operating parts and prevents rusting.

120 One of the very beneficial features of my

construction is the form of joint between the tool holder and the sheath. It has usually been customary to provide a simple threaded joint between these parts. In view 5 of the fact that the operator very frequently exerts pressure on the handpiece at an angle to the axis of the tool, this form of threaded joint permits rotation of the tool holder on the sheath. This is exceedingly 10 annoying. If the tool holder is screwed sufficiently tightly upon the sheath to prevent accidental rotation, it is exceedingly difficult to remove it. Frequently tools must be used to accomplish this removal, and this involves 15 delay in addition to damaging the finish on the holder and sheath.

From the foregoing description it will be readily evident that I have produced a dental operating piece which is exceedingly simple 20 in construction, easily assembled and disassembled, and convenient and efficient in operation.

I am aware that many changes may be made in the construction and arrangement 25 of the various parts without departing from the spirit of my invention, and I reserve the right to make all such as fairly fall within the scope of the following claims.

I claim as my invention:

30 1. In a dental handpiece, a tool holder provided with a socket to receive a tool, and means for locking said tool within said socket comprising a latch plate provided with an open ended slot to admit and interlock with said tool, and fasteners on said holder adapted to engage said plate on opposite sides of said slot when said plate is in locked position.

2. In a dental handpiece, a tool holder 40 provided with a socket to receive a tool, and means for locking said tool within said socket comprising a latch plate pivotally mounted on the rear face of said holder, an arcuate slot in said plate communicating with one edge thereof to receive and engage the projecting end of said tool, a second arcuate slot in said plate on the opposite side of the first slot from the pivotal connection, and a headed screw projecting from said rear face and adapted to enter said second slot when said plate is in latched position to firmly position said plate on said holder.

3. In a dental handpiece, a tool holder 55 provided with a socket to receive a tool, and means for locking said tool within said socket comprising a latch plate pivotally mounted on a headed screw on the rear face

of said holder and detachable therefrom without removing said screw, an arcuate 60 slot in said plate communicating with one edge thereof to receive and engage the projecting rear end of said tool, a second arcuate slot in said plate disposed on the opposite side of the first slot from the pivotal 65 connection, and a second headed screw projecting from said rear face and adapted to enter said second slot to firmly hold said plate on said holder when said plate is moved into latched position.

4. A dental tool holder comprising an angle piece having a transverse socket formed in the outer end portion thereof, a tool operating sleeve insertible into said socket from the rear end thereof, a shoulder on said sleeve co-acting with a corresponding shoulder in said socket to determine the advance of said sleeve within said socket, and a latch plate 70 slidable into position to retain said sleeve within said socket and a tool within said sleeve.

5. A dental operating piece comprising a handpiece, a driving spindle revolvably mounted in said handpiece, an angle piece 85 slidable over the outer end of said handpiece, a transverse socket in said angle piece near the outer end thereof, a revoluble tool holder in said socket, and driving mechanism operatively connecting said spindle with said tool holder.

6. A dental operating piece comprising a handpiece, a driving spindle revolvably mounted in said handpiece, an angle piece 90 slidable over the outer end of said handpiece, a latch for attaching said angle piece to said handpiece, a transverse socket in said angle piece near the outer end thereof, a revoluble tool holder in said socket, and shafting operatively connecting said spindle with said tool holder.

7. A dental operating piece comprising a substantially tubular casing, a transverse socket in said casing near the outer end thereof, a tool holding member revolvable within said socket, and a latch for retaining said member in said socket and a tool in said member.

8. A dental operating piece comprising a substantially tubular casing having a transverse socket near its outer end, a tool operating sleeve insertable into said socket from the rear end thereof, and a latch for retaining said sleeve in said socket and a tool in said sleeve.

WILLIAM L. THIEDEMANN,
